Patented Mar. 25, 1975

234,646

SOFT SURFACE FLOOR COVERING OR SIMILAR ARTICLE

Philip Nugent, New York, N.Y., assignor to Congoleum
Industries, Inc., Kearny, N.J.

Filed Feb. 15, 1973, Ser. No. 332,780

Term of patent 14 years

Int. Cl. D6—04

U.S. Cl. D92—4

FIG. 1

FIG. 2

FIG. 3

FIG. 1 is a top plan view of a soft surface floor covering showing my new design, the design unit being indicated with dash lines, which unit repeats in regular succession beyond the unit boundaries;

FIG. 2 is a view of a portion of FIG. 1; and

FIG. 3 is another top plan view of the soft surface floor covering showing my new design and on a slightly larger scale than FIG. 1, the design unit being indicated with dash lines, which unit repeats in regular succession beyond the unit boundaries.

I claim:

The ornamental design for a soft surface floor covering or similar article, substantially as shown and described.
